(57) **CLAIM**

We claim a new and ornamental design for metal fittings for bags, as shown and described below.

DESCRIPTION

The present article to which the design is to be applied is a metal fitting for bags used for fastening a flap portion of a

bag, which is made of material such as cloth, leather, or the like. The article is used by combining a body portion (a male portion) provided with a rotating portion and two fittings (female portions) attached at each end of a belt for fastening a flap of a bag. A flap of a bag can be fastened by laying the two fittings (the female portions) on top of the body portion (the male portion). A point of the rotating portion is a ring to which jewel(s) such as precious stone(s) or synthetic jewel(s) are attached.

FIG. 1 is a front view of a metal fitting for bags.

FIG. 2 is a rear view of the metal fitting for bags.

FIG. 3 is a right side view of the metal fitting for bags, the left side view being a mirror image thereof.

FIG. 4 is a top view of the metal fitting for bags, the bottom view being a mirror image thereof.

FIG. 5 is a reference view illustrating the state of the metal fitting for bags before rotating a rotating portion.

FIG. 6 is a front view of a male portion of the metal fitting for bags.

FIG. 7 is an A—A cross sectional view of the male portion of the metal fitting for bags.

FIG. 8 is a rear view of the male portion of the metal fitting for bags.

FIG. 9 is a top view of the male portion of the metal fitting for bags, the bottom view being a mirror image thereof.

FIG. 10 is a right side view of the male portion of the metal fitting for bags, the left side view being a mirror image thereof.

FIG. 11 is a front view of a female portion of the metal fitting for bags.

FIG. 12 is a rear view of the female portion of the metal fitting for bags.

FIG. 13 is a right side view of the female portion of the metal fitting for bags.

FIG. 14 is a left side view of the female portion of the metal fitting for bags; and,

FIG. 15 is a top view of the female portion of the metal fitting for bags, the bottom view being a mirror image thereof.
